UNITED STATES PATENT OFFICE

ELOI SOUCIE, OF MISSOULA, MONTANA

IRONING BOARD AND CLOSET CONSTRUCTION

Application filed December 21, 1931. Serial No. 582,437.

This invention relates to a novel built-in ironing board and concealing protective closet combination. It is a matter of common knowledge that retractible and projectible duplex ironing board ensembles in combination with concealing closets are not new, for which reason I feel called upon, by way of introduction, to state that the present inventive construction comprehends appreciable refinements and improvements in an arrangement of this class calculated to better fulfill the requirements of such a construction.

One feature of the improvements is predicated upon the novel guide and retention means for the main board in conjunction with a highly practical type of prop for said board and a feasible operating connection between the prop and board, wherein said parts are explicitly designed and co-operative to facilitate adjustment and operation.

Other structural features and advantages of the invention will become more readily apparent from the following description and the accompanying drawings.

In the drawings:

Figure 1 is a front elevation with the closet closed and the board concealed therein.

Figure 2 is a view in section and elevation disclosing the construction and relationship of parts.

Figure 3 is an enlarged fragmentary section and elevation disclosing the relationship of parts when the boards are collapsed completely within the closet.

Figure 4 is a horizontal section.

Figure 5 is a front elevation of the swingably mounted prop for the main board.

In the drawings, the closet is generally designated by the numeral 6 and the hinged door by the numeral 7. These parts may be of any suitable construction.

Referring to the interior of the closet however, it will be observed that I provide two sets of battens or rails for each vertical sidewall of the closet. These battens are in the nature of wooden strips of appropriate dimensions, the innermost strip being denoted by the numeral 8, the outermost strip at 9, and the intermediate strip at 10. This triple arrangement of strips provides an inner per-

pendicular guideway 11, and an outer guide channel 12.

The intermediate portions of the innermost edges of the strips 10 are formed with inclined notches 13 defining keeper seats for keeper studs 14 carried by the inner enlarged end portion 15 of the small sleeve board 16. Along longitudinal edges of this widened part 15 are reinforcing metal straps 17 as seen in Figure 4 and pivotally connected to these straps and depending therefrom are supporting links 18. This sleeve board 16 is independently operable with respect to the main ironing board 19.

Pivottally attached to the inner end of this board 19 are self-adjusting guide and retaining shoes 20, and these are shaped to ride up and down in the guideways 12 and to assume an inclined or canted state as represented in Figure 2 to support the board 19 in a horizontal operative position. In this connection I call attention to the inner edges of the strips 9 which are serrated so that the serrations define vertically spaced stops 21 with which the lower butt ends of the retaining shoes or cleats 20 co-operate.

It is to be observed that the pivotal connection between the shoes and adjacent inner end of the board 19 is at a point between the center and the lower ends of said shoes so that when the board 19 is in a horizontal supporting position as seen in Figure 2 and it is desired to drop it back into the cabinet, all that is necessary is to impart a sharp blow to the outer free end of said board, thereby exerting an inward thrust against the lower end portion of the shoes 20 to unseat the shoes and to allow them to ride downwardly to the lower ends of the guideways 12.

In setting the board 19 it is drawn perpendicularly up to the desired elevation and then suddenly pulled outwardly so as to trip the shoes 20 into a retaining position as represented in Figure 2.

The prop 22 comprises a panel having its lower end bifurcated. The furcations 23 are fixedly pivoted to the lower end portions of the strips 9. The upper end is also bifurcated and the furcations are provided with anti-friction rollers 24 engageable slidably

- with the underside of the board 19. The intermediate portion is formed with a kerf 25 in which the lower end portion of an operating link 26 is pivoted as indicated at 27. 5 The opposite end of the link is pivoted at 28 in a similar kerf 29 formed in the inner end of the board 19. In this way, an operating connection is afforded between the prop and the main board so that when the latter 10 is pulled up and out the link 26 automatically adjusts the prop to an inclined board sustaining position. The aforesaid legs or links 18 on the small sleeve board are pivotally connected to the inner end of the board 19. 15 It is obvious however that the sleeve board 16 is independently adjustable. In other words it may be either confined in the closet or swung out to vertical superposed position above the main board as represented in Figure 2 according to the discretion of the user. 20 It is obvious from the foregoing that there are actually two ironing board units, the main unit comprising the board 19, prop 22, operating link connection 26, and shoes 20 25 movable in the guideways 12; together with the small board unit having its individual retaining means and guideways as well as supporting links or legs 18. Both boards however are disposed to co-operate in a simplified and dependable manner. 30 Novelty is thought to reside in the guideways 12 of a closet wherein the outer guide defining strips 9 are serrated so that the serrations perform as vertically superposed stops for adjustable selective co-operation of the shoes 20. A further point of novelty is believed to be found in the particular shape of the elongated cleat-like shoes 20 having one bevelled end co-operating with the adjacent edges of the strip 10 and the other butt end selectively engageable with the stop 21, in conjunction with a pivotal connection between the inner end of the board 19 and said shoes 20 wherein the pivotal connection is 40 disposed between the center and butt end of said shoes. 45 Moreover, individuality of construction is believed to reside in the fixedly pivoted roller equipped prop 22 which is self-adjusting through the action of the novel adjusting and stay link 26, all of these parts being 50 carefully selected and mechanically joined to share proportionately in producing a simplified structure which is positive and dependable in action, smooth in operation, and otherwise efficient in performance in fulfilling the desired result of a structure of this class. 55 In each board, the underside is formed with grooves or channels, and the marginal edge portion of the cover 30 is rolled around individual keeper rods 31 which are forced into the channels and held in place. Accordingly, the board covers can be removed and 60 replaced expeditiously for sake of cleanli- ness. The drawings show but two end grooves with the rod therein, and as the means for attaching the cover to the board forms no part of my invention, it is not thought that further illustration of such means is necessary. 65 It is thought from the foregoing description that the advantages and novel features of the invention will be readily apparent. 70 It is to be understood that changes may be made in the construction and in the combination and arrangement of the several parts provided that such changes fall within the scope of the appended claims. 75 I claim: 80 1. In a structure of the class described, in combination, an open front closet formed with opposed vertical guideways along its opposite sides, an ironing board, a pair of duplicate cleats pivotally connected to the inner end of said board and movable in said guideways, said guideways being fashioned with stops with which said cleats are adjustably and releasably engageable, a prop having its lower end fixedly pivoted in the closet and its upper end slidably contacting the underside of the inner end portion of the board, and a link pivotally connected to the inner end of the board and intermediate portion of the prop for automatically setting the prop. 85 2. In a structure of the class described, in combination, an open front closet, a closing door therefor, pairs of opposed vertical strips fastened to the interior of the side walls of said closet and spaced apart to define vertical guideways, the inner edge of the two outer strips being serrated and said serrations defining vertically spaced retaining stops, a pair of duplicate block-like shoes slidable and tilttable in said guideways, an ironing board having its inner end pivotally connected to the intermediate portion of the shoes, in a manner to permit the shoes to be elevated without obstruction to the desired point and then canted diagonally with respect to the longitudinal center of the guideways for holding the board and shoes in a predetermined selected position, a prop comprising a panel fixedly pivoted at its lower end between the outer strips, anti-friction rollers on the upper end portion of the prop slidably contacting the underside of the board, a link pivotally connected at its upper end to the inner end of the board and pivotally connected at its lower end to the intermediate portion of the prop. 90 3. In an ironing board and cabinet construction of the class described, a vertically elongated open front cabinet having a hinged closing door, two groups of strips secured to the inner surfaces of the vertical side walls of said cabinet, to form guideways, the inner edges of the outer strips being serrated to provide vertically spaced seating stops, a pair of block-like shoes, slidable in 95 100 105 110 115 120 125 130

the guideways, each shoe comprising a block having a bevelled end and a butt end, the butt end being adapted to engage the stops selectively and the bevelled end to bear against the inner walls of the guideway to allow said shoes to move either up and down in the guideways or to assume canted retaining positions, an ironing board having its inner end portion pivoted to the intermediate portion of said shoes, the point of connection being between the center and butt ends of the shoes, a prop fixedly pivoted between the lower end portions of the outermost strip, anti-friction rollers secured to the upper end portions of said prop and slidably contacting the underside of the board when the latter is in operative position, a prop actuating and stay link pivotally connected at its upper end to the inner end of the board and at its lower end to the intermediate portion of the prop.

In testimony whereof I affix my signature.
ELOI SOUCIE.
